UNITED STATES PATENT OFFICE.

LOUIS NEUBERGER, OF BRIDGEPORT, CONNECTICUT.

DESIGN FOR A HOSE-SUPPORTER.

SPECIFICATION forming part of Design No. 29,690, dated November 15, 1898.

Application filed November 8, 1897. Serial No. 657,881. Term of patent 7 years.

To all whom it may concern:

Be it known that I, LOUIS NEUBERGER, a citizen of the United States, and a resident of Bridgeport, in the county of Fairfield and State of Connecticut, have invented and produced a certain new and useful Design for Hose-Supporters, of which the following is a specification.

The accompanying drawing shows a perspective view of a supporter, illustrating my design.

The leading feature of my design resides in a hose-supporter, the same comprising the shape and configuration shown in the accompanying drawing.

In the drawing, 1 indicates the leg-band, which is made of flat material and ornamented with a buckle 2 and a clasp 3.

4 represents the front triangular loop, to which the ends of the band are connected. 20 Said front is formed of round material and provided with small loops 5, formed in the upper corners, and which are ornamented with rings 6, as shown. To the lower end of the front is secured a metallic clasp 7 of the shape 25 illustrated in the drawing.

What I claim is—

The design for a hose-supporter, substantially as herein shown and described.

Signed at Bridgeport, in the county of Fairfield and State of Connecticut, this 19th day of October, A. D. 1897.

LOUIS NEUBERGER.
